CYCLIC SAFETY CONTROL FOR BURNERS
AND THE LIKEGeorge D. Bower, University City, Mo., assignor
to Automatic Control Corporation, St. Louis,
Mo., a corporation of Delaware

Application November 22, 1940, Serial No. 366,512

28 Claims. (Cl. 158—28)

1

This invention relates to a control for a heat-change device, particularly a burner such as an oil or a gas furnace, but capable in whole or in part of more general application.

The mechanism includes generally a device subject to movement upon change of heat, a space or room thermostat, a relay, here operated with a transformer in connection with the space thermostat, a timing or control motor, and a series of cam-operated switches controlled by the timing motor. The mechanism is used with an ignition device and a fuel supply device or air supply device, or both, generally designated a burner motor or burner operating device.

The mechanism provides a starting period, a running period and a scavenging period. In normal operation, upon demand by the space thermostat a starting period is instituted, by an instituting circuit closed for a limited interval. After it is established it becomes independent of the room thermostat. It includes a first phase at the end of which, absent ignition, lock-out occurs, and a second phase, at the end of which, with ignition, a running period is established, dependent upon the room thermostat, if starting was effective. Upon satisfaction of the room thermostat, the running period yields to a scavenging period, at the end of which the mechanism stops prepared for a new operation.

If ignition is not effective at the beginning and during the second phase of the starting period, the mechanism assumes a lock-out position, as noted, requiring manual reset. Such manual reset establishes the scavenging period at the end of which the mechanism tries once again to start.

If ignition fails during the running period, the scavenging period is established, at the end of which the mechanism may attempt to restart, and if it fails, locks out. At the lock-out position, the entire mechanism is deenergized. It may be manually reset by a shifting of the cams.

If power fails during the interval of closure of the instituting circuit, upon restoration, the starting period continues. If power fails during the established starting period, upon restoration the mechanism operates through the remainder of the starting period, the scavenging period, and starts anew.

If power fails during the running period, upon restoration, the mechanism proceeds through the scavenging period, and restarts.

It will be observed that at the end of any operation, normal or abnormal, there is a scavenging period prior to restart. This is true even after lock-out.

The objects of the invention are to accomplish each and all of the above operations, and to do so with a simple and economical novel construction.

A further object of the invention is to provide

2 a control device readily adapted to secure either continuous or intermittent ignition.

A further object is to provide a cycle of this kind, with or without all of its details, operated with periods of fixed duration.

A further object is to provide in a mechanism of this kind, an ignition-responsive device directly controlling the burner motor; and to provide means to prevent continued operation of the mechanism and motor if the said device fails in either its hot or its cold position.

Further objects include the provision of a cycle means of this kind, insuring a scavenging period after each operation; and to provide a cycle having its lock-out occurring prior to the running period.

In the drawings:

Fig. 1 is a front elevation of the device mounted on a pipe;

Fig. 2 is a side elevation with the pipe in section;

Fig. 3 is a front elevation with the cover removed;

Fig. 4 is a horizontal section taken on the line 25 4—4 at the top of Fig. 3;

Fig. 5 is a vertical section taken on the line 5—5 at the right of Fig. 3;

Fig. 6 is a vertical section taken on the line 6—6 of Fig. 5;

Fig. 7 is a front elevation of the casing with all the mechanism removed except the switch operated by the heat-change responsive device, mounted on the casing;

Fig. 8 is a rear elevation of the partition wall with the mechanism mounted thereon;

Fig. 9 is a section on the line 9—9 of Fig. 4 showing only the front cam and its switches;

Fig. 10 is a section on the line 10—10 of Fig. 4 showing the middle cam and its switches;

Fig. 11 is a section on the line 11—11 of Fig. 4 showing the rear cam and its switches;

Fig. 12 is a diagram of the program of the mechanism; and,

Fig. 13 is a general wiring diagram of the mechanism.

The mechanism includes an encased unit 40 having a heat-responsive device 41 projecting from the back thereof and supported in a pipe 42 so as to be influenced by heat changes therein. The mechanism 41 is almost instantly responsive to all changes in heat taking place at or above a given rate and reversing the heat condition from hot to cold or cold to hot; and it is of the type shown in co-pending application No. 328,177, filed April 6, 1940, Patent No. 2,323,370, issued July 6, 1943.

Recapitulating briefly from said applications, the stack unit includes an outer tube and an inner member preferably also a tube. The two may have the same coefficient of expansion. The

outer tube is located so as to receive immediately the relatively unlimited supply of heat if the burner ignites and produces flame, such as in the furnace stack, and desirably is of thin material so as to respond almost instantly to rapid changes in temperature such as may occur in normal starting or stopping of the flame; and it may also respond to fluctuations in heat of the flame.

The inner member is exposed at most only at its outer end to the flame, and contains an inner portion connected to a cold reservoir, as the switch casing and the control casing. The two members are secured together toward their outer ends, and preferably the heat from the flame reaches the inner member in its major portion from the outer member. Heat applied to the outer tube causes it to expand. A portion of this heat is transmitted to the inner tube, but that tube does not expand as much, owing to its dissipation of heat into the cold reservoir. Hence their will be a relative movement of the inner ends of the members causing the snap switch to operate to its closed position. In the starting position of the tubes, the snap switch is held in an intermediate position, so that it may move in either direction, and stay there under the influence of the snap-action means.

Continued application of heat to the tubes will never bring them to the same length, owing to the constant dissipation of the limited amount of heat supplied to the inner. Even if the inner tube should heat to a point of providing approximately the same length differential as at the start, the switch will not shift, as the starting condition has the switch floating at a mid-point of the snap-action means. Not until a positive reversal of the length differential occurs can the switch be moved, by overcoming the force of the snap-action.

If the flame stops, the outer tube will rapidly cool, but the inner tube cannot cool so rapidly. This reverses the length differential, and the outer tube, therefore, displaces the inner, returning the switch to its first position. Continued cooling does not change this, because even in the initial position the length differential would only put the switch into neutral position, and the force of the snap-action is ordinarily adequate to prevent even this.

It will be seen that the device will thus function upon any sudden heat change reversing the length differential, regardless of the temperature. Normal fluctuations or modulations occur at too slow a rate to cause the function. For instance, in a relatively slow decline of heat, the rate of heat dissipation from the outer member is less than the rate of heat dissipation from the inner, or at least is not so much greater a rate as to cause displacement of the end of the inner tube sufficient to move the switch to a point wherefrom it will snap over.

The unit itself has a main casing having a rear wall 43, side walls 44 and 45, top wall 46 and bottom wall 47. The side walls do not extend forwardly as far as do the top and bottom walls and have inwardly extending flanges upon which is mounted a partition wall 48 that provides an inner chamber 49. A U-shaped cover 50 fits over the top and bottom walls and back to the side walls to enclose a switch chamber.

The mechanism itself includes generally the heat change responsive unit 41, a switch 53 operated thereby, the switch being of the type disclosed in copending application, No. 328,177, filed April 6, 1940, having four terminals. The mecha-

nism also generally includes a control motor or timing device 54, a transformer 55 and a relay 56, the last three being mounted on the back of the partition wall.

The switch 53, as noted, has four terminals. The pair of terminals 57 are closed by the switch upon increase of heat applied to the unit 41, and the pair of terminals 58 are closed upon decrease of heat.

The control motor 54 operates three banks of control switches that are supported on the front side of the partition wall 48. The motor itself is mounted on a bracket 60 secured to the partition wall. The motor has a driving gear 61 (Fig. 6) that, in turn, drives a gear 62 fitted within an opening in the partition wall. The ratio of these gears determines the spread of the cycle, which, therefore, may readily be changed. A ratchet dog 63 on the gear 62 is spring-pressed into engagement with a ratchet 64 integral with a hollow cam shaft 65 that projects through the partition wall toward the front of the mechanism.

It will be seen that rotation of the gear 61 in a counterclockwise direction, in Fig. 6 looking from the back, will cause the gear 62 to rotate in a clockwise direction which, through the medium of the ratchet, causes corresponding rotation of the cam shaft 65. Looking from the front, as in Figs. 4 and 9-11, the cams rotate counterclockwise.

The cam shaft supports three cams, a front cam 67, a middle cam 68 and a rear cam 69. The cams are maintained in spaced relation and have a noncircular opening fitting over the noncircular cam shaft 65. A shield 70 shields off the opening through the partition wall 48 in which the gear 62 fits.

Within the hollow cam shaft is a shaft 71 on which is mounted a knob 72. This knob is like the one in copending application, No. 328,177, filed April 6, 1940, and is designed to permit only a limited movement of the knob. The knob also has a projecting leaf spring 73 at the back thereof that is adapted to engage at certain times with a button 74 on the front cam 67. By this means in a manner the same as described in the mentioned copending application, the knob 72 may rotate the cams in a counterclockwise direction a distance limited to the permitted movement of the knob 72. Release of the knob thereafter allows it to spring back into starting position.

The front cam 67, as shown in Fig. 9, has a lobe 83, a deep notch 84 and an edge 85 between the notch 84 and the lobe 83. This cam operates two switches 86 and 87. There is a cam follower arm 88 having a contact 89 adapted to close with the contact 88 on a blade 91 to constitute switch 86. The blade 91 is limited in its movement by a stop blade 92.

A spacer member 93 on the arm 88 holds an additional blade 94 spaced from the arm 88. This blade has a contact 95 adapted to engage with the contact 94 on a spring blade 97 which also has a stop blade 98 to form switch 87.

When the follower is on the lobe 83, the switch 86 is open, and switch 87 is closed. When the cam drops the follower to the edge 85, both switches are open, and when it further drops the follower into the notch 84, the switch 86 closes.

Referring to Fig. 3, it may be seen that all of these several blades are supported on the partition wall between two brackets 100 and 101. Each switch blade carrying a contact is insulated 75 from the others by a series of insulating blocks

102, and each blade also extends back of the brackets and insulating blocks to provide terminal portions to receive connections. The several banks of switches are spaced in accordance with the spacing of the several cams and all are insulated and connected, as will be obvious, to obtain the objectives of the wiring diagram.

The middle cam and its switches are shown in Fig. 10. The cam 68 has a lobe 104 from which there extends a somewhat lower lobe 105 followed by a low edge 106, and then a notch 107.

This bank of the switches includes three switches 108, 109 and 110. There is a follower arm 111 that has a contact 112 adapted to close with a contact 113 to form the switch 108. The contact 113 is mounted on a switch blade 114 having a stop blade 115 to limit its movement.

The arm 111 is provided with a spacer member 116 by means of which it is held in spaced relation to a spring blade 117 having a contact 118 that is adapted to close with a contact 119 to form the switch 109. The contact 119 is secured to a spring blade 120 that has a stop blade 121.

The contact 119 has an opposed contact 122 on the blade 120 that is adapted to close with a contact 123 to form the switch 110. The contact 123 is secured to a spring blade 124 which has a stop blade 125. The several blades are mounted between the brackets 100 and 101 and are duly insulated from each other, as shown. They are also provided with suitable terminal ends to receive connections.

When the cam 104 is in the position shown, the switch 108 is closed and the switches 109 and 110 are open. When a short time later the cam lifts the follower out of the notch 107 onto the edge 106, it opens the switch 108 without closing 109 or 110. Sometime thereafter, the edge 105 lifts the follower to close the switch 109, and, upon reaching the edge 106, also closes the switch 110.

The rear cam 69 (Fig. 11) has a lobe 130 followed by an edge 131 that is quite low, and between the edge 131 and the lobe 130 there is a medium-high edge 132. This cam operates switches 133, 134 and 135. It has a follower arm 136 with a contact 137 adapted to engage with a contact 138 to form the switch 133. The contact 138 is secured to a switch blade 139 and there is a stop blade 140 to limit the movement thereof.

The follower arm 136 also has a second contact 141 adapted to be engaged with the contact 142 on a blade 143 to form the switch 134. A spacer member 145 holds the blade 143 spaced from another blade 146 that has a stop blade 147 to limit its movement. The blade 146 has a contact 148 adapted to close with the contact 149 on a blade 150 to form the switch 135. The blade 150 also has a stop blade 151 to limit its movement.

When the position shown in Fig. 11 is attained, the switches 134 and 135 are closed. When the cam rotates so that the follower 136 drops to the edge 131, switches 134 and 135 will snap open and the switch 133 will close. Thereafter, when the cam presents the middle edge 132 to the follower arm, it opens the switch 133, but does not close the switches 134 and 135. These two switches are reclosed by the cam lobe 130.

The transformer 55 includes a primary 160 and a secondary 161, as shown in the wiring diagram.

The relay 56 includes a coil 162 that, when de-energized, releases an armature 163 that is biased to close with the contact 164, and to open the switch 166. When the relay is energized, the

5 armature is closed with the contact 165, and the switch 166 is closed also.

The relay coil 162 is in series with the secondary of the transformer and also with the room thermostat 167.

The unit itself on the front of the partition wall 48 has six terminals. The terminals 170 and 171 are adapted to be connected to the leads from the room or space thermostat. The terminals 172 and 173 are the power lines. From the terminal 174 goes one line to the burner motor, the other line of which is brought back to the ground power line 173, and from the terminal 175 goes one lead to the igniter mechanism, the other from which also goes to the ground power line 173. The two ground lead lines from the igniter and burner motor may, if desired, be connected to the terminal 173. The remaining connections will be clear from the accompanying wiring diagram.

It will be seen that one terminal 57 of the stack unit is connected to the switches 87 and 108, and to the terminal 174. The other terminal of the switch 103 leads to a bracket 177 (Fig. 5) attached to the partition 48, and overlying in spaced relation an extension of the terminal 175. A screw 178 passes through the extension and is adapted to contact the bracket 177 when tightened, or to be spaced therefrom when loosened. This screw forms a selective switch 179, and determines whether or not the igniter operates continuously through the running period, or stops at the end of the first phase of the starting period.

The operation of this cycle is shown in Fig. 12. At the start, the cams present the several points "S" to their followers. Reference to the program and to the other figures will show that switches 87, 108, 110, 133, 134 and 135 are open, and switches 86 and 109 are closed by their cams, establishing an instituting circuit through the primary winding 160. The heat switch 58 is closed because the unit 41 is cold, and the switch 163 is released against the contact 164. When the room thermostat switch 167 closes, demanding heat, the secondary coil 161 causes the flow of current through the thermostat switch to the relay coil 162. This closes the switch 163 against the terminal 165, and also closes the switch 166.

Thereupon, a circuit to the control motor is established from the terminal 172, switch 163, 50 switch 109, through the control motor to the terminal 173. The control motor then begins to operate and to rotate the cams. After about two and a half seconds of operation of the control motor, the switches 110, 134 and 135 close; 55 Closing of the switch 134 shunts the switch 163 and holds its circuits independently of the coil 162 and, hence, of the room thermostat, thus insuring that, for the interval of closure of the switches 134 and 109, the control motor will continue to operate. Also, there is an additional holding circuit for the primary 160 of the transformer which is independent of the switches 86 and 58, and which includes either the switch 134 or the switch 163, the switch 109, the switch 60 135, the switch 166 and the primary 160.

Closing of the switch 110 puts the ignition device in circuit directly in parallel with the control motor. The igniter thereupon begins to operate. After the lapse of about twelve and 70 one-half seconds, the switch 86 opens and the switch 87 closes. Opening of the switch 86 has no effect at this time because of the previously established holding circuit to the coil 160 through the switch 135. It does prevent reclosing of the 75 primary circuit upon lock-out or after the run-

ting period, and thereby insures that the switch 163 will remain against contact 164 to insure the scavenging period, as will be seen. Closing of the switch 87 establishes the circuit to the burner motor which includes either the switch 134 or the switch 163, the switch 109, the switch 135, the switch 87 and the burner motor. When the burner motor starts, fuel is supplied and in due course will be ignited by the igniter. It is to be observed that the igniter is operated prior to the burner motor, a desirable safety feature.

When the ignition takes place, the stack switch operates almost instantly so that the switch 87 is closed and the switch 88 is opened. This then establishes a circuit to the burner motor by way of either the switch 134 or the switch 163, and the switch 87. It also establishes an additional circuit to the coil 160 from the switch 87 and through the switch 87 and the switch 166. It likewise establishes an additional circuit to the control motor from the switch 87, the switch 87 and the switch 135, and additionally establishes a circuit to the igniter through the switch 110.

After the lapse of a period of sixty seconds, the first phase of the starting period, the switches 109 and 110 open and the switch 108 closes. Opening of the switch 108 breaks its circuit to the control motor, but that motor continues because of the alternative circuit through the switch 87. This circuit holds the coil 160 through the switches 87 and 166, the control motor through the switches 87 and 135, ignition device through switch 108, and the burner motor. Thereupon, the continued holding of the circuits depends upon the continued flame to hold the stack switch 87 closed.

Thus, continued operation of the normal cycle depends upon the condition at the end of sixty seconds. If normal ignition takes place, the mechanism will continue for an additional ten seconds' interval, until the lapse of seventy seconds, at which time the switches 134 and 135 will open and the switch 133 will close. This interval is the second phase of the starting period. It is a lock-out period. Closing of the switch 133 has no effect as long as the switch 163 is closed against the contact 164. Opening of the switch 134 leaves the circuit dependent upon the position of the switch 163 and, therefore, upon the condition of the room thermostat. Opening of the switch 135 has no effect on the coil 160 as long as flame continues, because of the alternate circuit to the coil through the switches 87, 87 and 166. It does, however, have an effect on the condition of the control motor which was previously in circuit only through the switch 135. This motor, therefore, stops. The ignition device remains in circuit through the switches 87, 108 and 178 if the latter is closed. For some burners this is a desirable safety feature. For others, it is not necessary, and so, upon loosening the screw 178 to open the switch 178, the effect of the switch 108 in holding the igniter in circuit is nullified, and it ceases operation upon opening of the switch 110 at the end of sixty seconds. The switch 108 is held closed for a short time beyond the seventy-second point to insure operation of the igniter even when the control motor floats or coasts for an interval after deenergization.

When the control motor stops, the mechanism is in the operating or running stage, and is wholly dependent for continuance of this stage upon continued closure of the room thermostat, the stack

switch 87, and the relay switch 168. Of course, the timing motor switch 87 must remain closed.

As soon as the room thermostat is satisfied and opens, the coil 162 is deenergized, the switch 163 shifts to the contact 164, and the switch 168 opens. The fact that the instituting circuit is broken at the switch 86 prevents energization of the primary at this point, so that the switch 163 can shift. This cuts the primary coil 160 out of circuit. It cuts the burner motor out of circuit because it breaks the line to the switch 87. It cuts the ignition device out of circuit for the same reason. However, closing the switch 163 with the contact 164, with the closure of the switch 133, establishes a circuit through those two switches to the control motor which again begins to operate.

Very promptly (preferably and normally a matter of seconds) after the burner motor stops, the heat will drop at the stack unit 41 at a great rate so that the switch 88 closes and the switch 87 opens. This has no effect on the established circuits.

After the lapse of five more seconds or, disregarding the running period, seventy-five seconds from the start, the switch 108 opens. This has no immediate effect. Continuing the switch 108 beyond the seventy-second point assures operation of the igniter, despite the floating or coasting interval of the control motor. This, of course, assumes that the switch 178 is closed. After the lapse of eighty seconds, the switch 87 opens with no immediate effect. The switch 87 likewise accommodates the coasting period.

The control motor alone will continue to operate until almost the end of the entire cycle, which cycle is here shown at 240 seconds. This insures a long scavenging period to take care of all unburned fuel.

After the lapse of 230 seconds, the switch 109 again closes. This has no effect, because the switch 163 is closed against the contact 164 and because even any circuit established through the switches 133 and 109 is broken at the switch 87, and any circuit to the switch 87 is broken at switch 134.

Thereafter, at 235 seconds, the switch 86 closes again to reestablish a circuit to the primary 160. The primary, however, is inactive because the room thermostat is open. No other circuits are established by this act.

At the end of 240 seconds, the switch 133 opens again and thereby all circuits other than the instituting circuit to the coil 160 open. The control motor stops and the mechanism awaits a new call by the room thermostat.

It has previously been noted that, after a sixty-second interval, the circuit is dependent upon ignition, because it is dependent upon the condition of the switch 87, which closes only upon the existence of ignition at the sixty-second point. If it be assumed that ignition does not exist at this time and that the switch 87 is open, the mechanism will stop after this lapse of sixty seconds. This is the lock-out position.

At this lock-out position, the button 74 on the front cam 67 has just passed under and is in front of the leaf spring 73 on the knob 72. The mechanism can be reoperated only by manual rotation of this knob counterclockwise as far as it will go, here about 45°. It then may be released, and will automatically return to its first position after having displaced the cams.

At the time the mechanism stops, prior to turning the knob, the switches 88, 134, 135, 108 and

87 are closed and switches 57, 86, 133, 109 and 110 are open. The switches occupy these positions in Figs. 9, 10 and 11. All circuits, including those to the primary 169, are open.

Rotation of the knob shifts the cam 67 until the lobe 83 is removed from the follower 88, which rests upon the edge 85. In this position, switches 86 and 87 are both open. Rotation shifts the cam 68 beyond the notch 107 until the follower 111 rides on the edge 106, in which position all of its switches 108, 109 and 110 are open. Rotation also shifts the cam 69 until its follower 136 falls onto the edge 131, in which switch 133 is closed, switches 134 and 135 open.

Thus, rotation of the knob advances the mechanism to a short distance beyond the start of the scavenging period, skipping the intermediate period and running period. The control motor is in circuit, and completes its cycle. Here, again, the fact that the switch 87 is open prevents operation of the relay, and enables the scavenging cycle to occur. If the room thermostat demands heat at the end of the cycle, the mechanism will start over again.

In case of flame failure during the running period, occasioned by break of fuel supply or any familiar cause, the igniter being in circuit will normally restart the flame before the failure is effective on the stack switch. If the stack switch cools to open the switch 57 and close the switch 58, during the running period, as switch 86 is open, the primary will be deenergized, the switch 163 will close with contact 164, the scavenging period will occur and the mechanism will return to starting position where it will be under control of the room thermostat. If the thermostat continues to demand heat, a new cycle will begin. If flame failure was due to some cause that prevents ignition in the new cycle, the mechanism will pass to the lock-out position.

In case of power failure and restoration during the first twelve and one-half seconds during which the switch 86 and the instituting circuit are closed, the mechanism will take up where it left off. Upon power failure between twelve and one-half and sixty seconds, the coils 160 and 161 will be deenergized, opening the switch 166, and shifting the switch 163 to the contact 164.

Restoration of power will produce circuits around the switch 163, through switch 134, but the coils will not be reenergized because the switch 166 is open. The control motor will run, through switches 134 and 109, the ignition device through switch 110, and the burner motor through switches 135 and 87. When the sixty point is reached, the switch 109 opens, but if ignition has occurred, the switch 57 has closed, and the burner motor continues through switches 134 and 57, with the control motor continuing through switches 134, 57, 87 and 135, and the ignition device through switches 134, 57 and newly closed switch 108. The cycle will continue to the seventy-second interval, the normal start of the running period. At this point, switches 134 and 135 open. This breaks the circuit to the burner motor, because the switch 163 is closed with contact 164. However, at this time, the switch 133 has closed, so that the normal scavenging period is established, and the mechanism will complete it and restart, if the thermostat demands. It thus may be said that the power condition at twelve and one-half seconds pre-determines what will happen at seventy seconds, viz., whether the running period will occur or not.

If power fails and is restored during the in- 75

termediate interval between sixty and seventy seconds, the coils 160 and 161 will be deenergized, switch 163 shifts to contact 164, and switch 166 opens. As the switch 133 is open at this time, lock-out will result, unless the power failure occurred so near the end of the intermediate period that the control motor coasted to a point closing the switch 133, and thereupon setting the mechanism for a scavenging operation upon power restoration.

If power fails and is restored during the running period, the coils will be deenergized, the switch 163 shifted to the contact 164, and the scavenging period started at once, returning the mechanism to starting position.

If power fails and is restored during the scavenging period, the mechanism will take up where it left off.

By considering the wiring diagram, it may be seen that the switch 86, when closed, permits the instituting circuit to be closed. The switch opens prior to lock-out to render the lock-out effective, since otherwise the circuit to the primary would not be broken by opening of the switch 109, and the control motor, ignition and burner motor could continue by circuits through switches 86, 58, 166, either 135 or 87, with 108 and 110. The switch 86 opens also to render the mechanism subject to power failure.

The switch 58 has the function of preventing recycling if the switch 57 fails in hot position, because the switch 58, under such circumstances, will be open, prohibiting closing of the instituting circuit, the two switches being mechanically disposed to be operated by the switch blade in opposite positions. If the switch fails cold, the instituting circuit will be broken, as noted, by the switch 86, and lock-out will occur.

The switch 134, as noted, insures a starting cycle up to lock-out once the control motor has operated to close it, regardless of the condition of the room thermostat. If ignition does not take place prior to opening of the switch 109, lock-out will occur. If ignition does occur, then the opening of the room thermostat will release the switch 163 to contact 165, and will open the switch 166, but the burner motor will remain in circuit through the switch 57, the control motor through 57, 87 and 135, until the switch 134 opens, and the switch 133 simultaneously closes, establishing the scavenging period. Hence, operation of the room thermostat during any phase of the starting period does not disrupt the normal cycle.

The switch 163 is a selector switch, determining whether the scavenging or operating circuits of the control motor shall function. It, of course, interlocks its circuits with the room thermostat, and the selection it makes is dependent upon the room thermostat. Likewise, it selects in response to flame failure, when it is dependent upon the switch 57 for its position, and it selects in response to power failure, when it is dependent upon the switch 166. Its holding circuit, being at times dependent upon flame switch 57, power failure switch 166, and the room thermostat 167, its selection depends upon the conditions of these switches.

The switch 166 is the power failure switch. As it controls the holding circuit for the room thermostat and the selector switch, it controls the entire mechanism for power failure. It is ineffective only when the instituting circuit is closed.

The switch 133 controls the scavenging opera-

tion. Upon failure of ignition, with lock-out, the selector switch drops over to scavenging position. If the switch 188 were not present, lock-out could not occur, as the scavenging cycle would start forthwith. Thus, the switch 188 spaces the start of scavenging from the point of lock-out.

The switch 188 is the lock-out switch. When closed, it provides the first phase of the starting cycle. When open, it causes lock-out, prior to closing of the scavenging switch 188.

The switch 185 controls the operation of the control motor circuit, after the lock-out switch has opened. After ignition has occurred, the switch 185 opens the circuit to the control motor. In this connection, a junction of the switch 88 is shown, in that it opens to break a circuit to the mechanisms through the switch 185 prior to ignition, this being a supplement to its previously mentioned manner of rendering the lock-out circuit effective.

The switches 118 and 188, the latter with the switch 178, control operation of the igniter.

The switch 87 has two primary functions. If it were not present, the initial burner motor circuit would be closed upon closure of the switch 185, prior to energizing the igniter, an obvious disadvantage. Also, if it were not present, there would be a burner motor circuit immediately upon closing of the room thermostat and the switch 188, through 88, 58, 188, the circuit across 87 and the burner motor. The switch 87 must be open during the effective period of the instituting circuit and until it is desired to energize the burner motor; it must be closed to operate the energizing circuit; and it must be closed during the second phase of the starting period and during the running period to close the holding circuit for the selector switch, the power failure switch and the room thermostat circuit.

The switch 87 is clearly a flame safety switch. Its being in series with the power failure relay holding switch causes it to control the entire mechanism, and when opened to effect deenergization of the entire mechanism, unless a proper recycling occurs. If it fails cold, lock-out results; if it fails hot, no starting can occur, as above noted in connection with its companion switch 88.

It will be seen that no separate power failure relay is here required, owing to the connections making the main relay into a power failure relay. The resistor shown controls the amount of current in the transformer and thermostat circuit.

In the foregoing, the object has not been to explain every function of each switch and each circuit, but rather to elucidate some of the purposes of the several parts. It may be noted, for instance, that the use of a choke coil and separate thermostat circuit to short circuit it as well as to receive a utilitarian current could be replaced by a direct connection of the thermostat and the relay coil. Other like substitutions could be made within the scope of the appended claims.

What is claimed is:

1. In a mechanism of the kind described, a fuel supply device, a thermostat, a circuit for the thermostat, a first switch in said circuit, a circuit for the supply device, including means connecting the supply device circuit into the thermostat circuit after the first switch, and dependent upon continued power to hold the thermostat circuit through said connection independently of the first switch, timing means to open the first switch and to close the fuel supply device circuit

5 at the same time, and means to start operation of the timing means upon closure of the thermostat circuit.

2. In a mechanism of the kind described, a fuel supply device, a timing device having a plurality of cam switches for producing a complete cycling operation of the fuel supply device, means including a cam operated switch adapted to be opened to stop operation of the timing device short of the end of the cycle, and means to displace the cam switches to cause restarting of the timing device.

3. In a mechanism of the kind described, a burner, a fuel supply device, a control means for the fuel supply device to provide a first period during which ignition may ordinarily occur and a running period for the burner, a power failure relay including a relay switch, means to cause energization of the relay to effect closure of the relay switch, a circuit through the relay switch for starting the control means, a shunt circuit closed by the control device after its operation has begun, to maintain the control device in operation for the first period independent of the relay, and means to prevent reenergization of the relay upon failure of power during the said first period, independent of the existence or lack of combustion.

4. In a mechanism of the kind described, a burner, a fuel supply device, a first control for the fuel supply device adapted for movement to open and closed positions, a second control means for the fuel supply device adapted to provide a first period during which ignition may normally occur, and a running period thereafter, a circuit for the second control means adapted to be closed upon closure of the first control means, means operated by the second control means to maintain the second control means in operation for said first period regardless of opening of said first control during said first period, and means to prevent the existence of the running period if the first control is opened during said first period during operation of said maintaining means.

5. In a mechanism of the kind described, a fuel supply means, a first control therefor, a second control adapted to provide a first period of operation of the fuel supply means during which ignition may occur, and a running period thereafter, said first control being operable to two positions, a first circuit for the second control through the first control in its first position, and a second circuit for the second control through the first control in second position, means to operate the first control to second position to cause operation of the second control through said second circuit, means operated by the second control means to maintain said second control in operation for the first period regardless of the position of the first control, and means maintaining said second control in operation after said first period through said first circuit, when said first control is in its first position at the end of said first period.

6. In a mechanism of the kind described, a fuel supply means, a first control therefor comprising a relay and a relay switch, the switch being actuated from a first position when the relay is deenergized to a second position when it is energized, thermostatic means operable to cause energization of the relay only when a predetermined temperature condition is reached, a second control adapted to provide sequentially a first period of operation of the fuel supply means during which ignition may occur, and a running

period thereafter, a first circuit for the second control through the relay switch in second position to start the second control, means operated by the second control means after its start to maintain said second control in operation for said first period regardless of said first control, a second circuit for the second control through the first control in first position, and said maintaining means being adapted to render the second control subject to continued operation through the relay switch in first position at the end of said first period when said relay switch has returned to its first position.

7. In a mechanism of the kind described, a burner, a fuel supply device therefor, a control means to provide a first period during which ignition may occur, and a running period for the burner, a power failure relay including a relay switch, means to cause energization of the relay to effect closure of the relay switch, a circuit through the relay switch for starting the control device, a circuit for starting the fuel supply device, means to maintain the control device and the fuel supply device in operation for the said first period independent of the relay, and means to prevent continued operation of the fuel supply device after said period upon failure of power and release of the relay during said period.

8. In a mechanism of the kind described, a burner, a fuel supply device therefor, a control means to provide a first period during which ignition may occur, and a running period for the burner, a power failure relay including a relay switch, means to cause energization of the relay to effect closure of the relay switch, a circuit through the relay switch for starting the control device, a circuit for starting the fuel supply device, means to maintain the control device and the fuel supply device in operation for the said first period independent of the relay, an additional circuit for the fuel supply means dependent upon the energization of the relay, the opening of said maintaining means rendering the fuel supply means dependent upon said additional circuit, and means to prevent reenergization of the relay once it has been released.

9. In a mechanism of the kind described, a burner, a fuel supply device therefor, a control means to provide a first period during which ignition may occur, and a running period for the burner, a power failure relay including a relay switch, means to cause energization of the relay to effect closure of the relay switch, a circuit through the relay switch for starting the control device, a circuit for starting the fuel supply device, means to maintain the control device and the fuel supply device in operation for the said first period independent of the relay, an additional circuit for the fuel supply means dependent upon the energization of the relay, the opening of said maintaining means rendering the fuel supply means dependent upon said additional circuit, and means to prevent reenergization of the relay once it has been released including means dependent upon existence of combustion to complete said additional circuit.

10. In a mechanism of the kind described, a burner, a fuel supply means therefor, a power failure means, a control mechanism adapted to provide a first period for the burner during which ignition may occur, an intermediate period, and a running period, means to cause starting of the fuel supply means during the first period, means dependent upon existence of combustion to maintain the fuel supply means in operation for the

intermediate period, and means dependent upon combustion for maintaining the fuel supply means in operation for the running period, means to maintain the control mechanism in operation for the first period independently of the power failure means, means to maintain the control mechanism in operation for the intermediate period independently of the power failure means but dependent upon combustion, and means to stop the fuel supply means but to maintain the control mechanism in operation after the intermediate period upon failure of power during the first period.

11. In a mechanism of the kind described, a fuel supply means to supply fuel to be ignited, control means to provide sequentially a starting period during which combustion may occur, and a running period, automatic means to start the control means, and means independent of said automatic means to cause recycling of the control means upon instantaneous failure of power and its restoration during the starting period.

12. In a mechanism of the kind described, a fuel supply means to supply fuel to be ignited, means responsive to existence of combustion to maintain said fuel supply means in operation, power failure means adapted to render the fuel supply means inoperative, and means to continue operation of the fuel supply means for additional time upon failure of power for an interval too short to cause the means responsive to combustion to render the fuel supply means inoperative.

13. In a mechanism of the kind described, a fuel supply device, a control mechanism adapted to provide sequential operations for the fuel supply device, a combustion-responsive device closed upon existence of combustion, means to effect starting of the control mechanism, circuit means through the combustion responsive device including a branch for the control mechanism and a branch for the fuel supply device, means in the control mechanism to render the control mechanism and fuel supply device dependent upon said circuit means, means in the control mechanism branch operated by the control mechanism to render the control mechanism inoperative, a power-responsive means having a switch controlling said circuit means, and a coil, said circuit means having a third branch providing a coil energizing means, and means under control of the control mechanism to maintain said third branch closed when the control mechanism branch is opened, and an additional circuit to the control means adapted to be closed through the power-responsive means switch when the coil is deenergized.

14. In a mechanism of the kind described, a burner, a combustion-responsive means operable to hot or cold positions, means to cause the burner to operate for a running period dependent upon the combustion-responsive means, means providing a scavenging period after the running period, said scavenging period means being adapted to operate after a running period whether or not the combustion-responsive means operates to hot or cold position, means to prevent re-establishment of operation of the burner unless the combustion-responsive means is in cold position, and means to insure capacity to recycle if the combustion-responsive means is in cold position.

15. In a mechanism of the kind described, a burner, a relay switch, a combustion-responsive switch, a control mechanism, means to operate the control mechanism to provide sequential op-

eration of the burner, a circuit for the burner including the relay switch and the combustion-responsive switch in series, whereby when either switch fails to function the burner may nevertheless be controlled by the other, and means to prevent restarting of the control mechanism upon failure of the relay switch and opening of the combustion-responsive switch.

16. In a mechanism of the kind described, a burner, a first control switch responsive to predetermined conditions, a combustion-responsive switch, a control mechanism including a plurality of sequentially operated switches, a first circuit including a control mechanism switch to maintain the control mechanism in operation for a predetermined interval, a second circuit means including the combustion-responsive switch to maintain the control mechanism and the burner in operation for an additional period, and a third circuit including the combustion-responsive switch and the first control switch in series to maintain the burner but not the control mechanism in operation after said additional period, whereby upon failure of either the combustion-responsive switch or the first control switch to open, the burner remains under control of the other switch.

17. In a mechanism of the kind described, a control device, a fuel supply device, a first switch, a second switch, said control device being adapted to maintain the first switch open when the second is closed, a first circuit including a branch to the control device and a branch to the fuel supply device, means to control said first circuit, to control both devices, said first switch being in the fuel supply device branch, and a second circuit for the control device including said second switch, whereby when the first switch is closed both devices may be energized through the first circuit, and when the first switch is open and the second closed, the control device may operate without operation of the fuel supply device.

18. In a mechanism of the kind described, a control device, a fuel supply device, a first switch, a second switch, an ignition-responsive switch, said control device being adapted to maintain the first switch open when the second is closed, a first circuit including a branch to the control device and a branch to the fuel supply device, means to control said first circuit to control both devices, said fuel supply device branch including said first switch whereby both devices may be operated through said first circuit when the first switch is closed, a second circuit to the fuel supply device including said combustion-responsive switch, whereby both devices may operate together through said second circuit when said ignition-responsive switch and first switch are closed, and whereby upon opening of the first switch said fuel supply device alone may be operated through the second circuit, and a third circuit for the control device including said second switch but not said first switch, whereby when the second switch is closed and the first open, the control device may be operated without the fuel supply device, and means to select the first or the third circuit.

19. In a mechanism of the kind described, a control device, a first circuit adapted to institute operation of the control device, a second circuit adapted to continue operation of the control device, a connection between the circuits and dividing the first circuit into two parts, means operated through the second part of the first circuit to control the closure of the second circuit, a first

switch in the first part of the first circuit, and a second switch in the second circuit, said second switch being adapted to be opened to break the second circuit, and means opening the first switch as early as the second switch is opened.

20. In a mechanism of the kind described, a control device, a first circuit adapted to institute operation of the control device, a second circuit adapted to continue operation of the control device, a connection between the circuits and dividing the first circuit into two parts, means operated through the second part of the first circuit to control closure of the second circuit, a first switch in the first part of the first circuit, and a second switch in the second circuit, said second switch being adapted to be opened to break the second circuit, and means opening the first switch as early as the second switch is opened, together with a fuel supply means, and a connection between the fuel supply means and the second circuit to cause operation of the fuel supply means when the second circuit is closed.

21. In a mechanism of the kind described, a control device, a first circuit adapted to institute operation of the control device, a second circuit adapted to continue operation of the control device, a connection between the circuits and dividing the first circuit into two parts, means operated through the second part of the first circuit to control closure of the second circuit, a first switch in the first part of the first circuit, and a second switch in the second circuit, said second switch being adapted to be opened to break the second circuit, and means opening the first switch as early as the second switch is opened, together with a fuel supply means, and a connection between the fuel supply means and both the first and second circuits, switch means in said last-named connection, and means to maintain said last-named switch means open during closure of the first circuit.

22. In a mechanism of the kind described, a control device, a first circuit adapted to institute operation of the control device, a second circuit adapted to continue operation of the control device, a connection between the circuits and dividing the first circuit into two parts, means operated through the second part of the first circuit to control closure of the second circuit, a first switch in the first part of the first circuit, and a second switch in the second circuit, said second switch being adapted to be opened to break the second circuit, and means opening the first switch as early as the second switch is opened, together with a fuel supply means, a connection between the fuel supply means and the second circuit to render the fuel supply means dependent upon the second switch, a third circuit means dependent upon combustion to maintain the fuel supply means in operation upon opening of the second circuit, a switch means in the last-named connection between the third and second circuits, and means to maintain said last-named switch means open when the first circuit is closed.

23. In a mechanism of the kind described, a control device, a first circuit adapted to institute operation of the control device, a second circuit adapted to continue operation of the control device, a connection between the circuits and dividing the first circuit into two parts, means operated through the second part of the first circuit to control closure of the second circuit, a first switch in the first part of the first circuit, and a second switch in the second circuit, said second

switch being adapted to be opened to break the second circuit, and means opening the first switch as early as the second switch is opened, together with a fuel supply means, a connection between the fuel supply means and the second circuit to render the fuel supply means dependent upon the second switch, a third circuit means dependent upon ignition to maintain the fuel supply means in operation upon opening of the second circuit, a switch means in the last-named connection between the third and second circuits, and means to maintain said last-named switch means open when the first circuit is closed, said third circuit including a switch means dependent upon the existence of combustion to be closed.

24. In a mechanism of the kind described, an operated device, a control mechanism including a plurality of switches, said control mechanism being adapted to operate the switches sequentially, circuit means including said switches, and adapted to provide sequentially a starting period, a lock-out, an intermediate period, and a return period, for the operated device, said switches being bodily displaceable independently of operation of the control mechanism, and means to displace the switches from lock-out position to return position.

25. In a mechanism of the kind described, a control mechanism having a plurality of sequentially operated switches, and means for operating the same, a fuel supply device, means including at least one of said switches to provide a starting period for the fuel supply device, means including at least one of said switches to provide a lock-out for said device, means including at least one of said switches to cause said control mechanism to restart after said lock-out, said switch operating means being displaceable independently of operation of the control mechanism, and means to displace said switch operating means independent of the control mechanism from the lock-out position to the restart position.

26. In a control mechanism, a control means operable in response to predetermined conditions, including a switch, a fuel supply device, a timing means, a first timing means switch, a second timing means switch, a combustion-responsive switch, a first circuit to the timing means including the control means switch, the first timing means switch, and the timing means, a second circuit for the fuel supply device including the control means switch, the combustion-responsive switch, and the fuel supply device, a connection leading from the second circuit after the combustion-responsive switch to the timing means, said connection including the second timing means switch, said timing means being adapted to have its first switch to be closed at the start of a cycle and to open a time interval thereafter, and being adapted to close its second switch before opening of its first switch, and to open it a time interval after opening of the first timing means switch.

27. In a control mechanism, a control means operable in response to predetermined conditions, including a switch, a fuel supply device, a timing means, a first timing means switch, a second timing means switch, a combustion-responsive switch, a first circuit to the timing means including the control means switch, the first timing means switch, and the timing means, a second circuit for the fuel supply device including

the control means switch, the combustion-responsive switch, and the fuel supply device, a connection leading from the second circuit after the combustion-responsive switch to the timing means, said connection including the second timing means switch, said timing means being adapted to have its first switch to be closed at the start of a cycle and to open a time interval thereafter, and being adapted to close its second switch before opening of its first switch, and to open it a time interval after opening of the first timing means switch, plus a third timing means switch and connections including the same to shunt the control means, said timing means being adapted to close said third switch after the timing means has started, and to open the same after a predetermined interval during which combustion may occur.

28. In a control mechanism, a control means operable in response to predetermined conditions, including a switch, a fuel supply device, a timing means, a first timing means switch, a second timing means switch, a combustion-responsive switch, a first circuit to the timing means including the control means switch, the first timing means switch, and the timing means, a second circuit for the fuel supply device including the control means switch, the combustion-responsive switch, and the fuel supply device, a connection leading from the second circuit after the combustion-responsive switch to the timing means, said connection including the second timing means switch, said timing means being adapted to have its first switch to be closed at the start of a cycle and to open a time interval thereafter, and being adapted to close its second switch before opening of its first switch, and to open it a time interval after opening of the first timing means switch, plus a scavenging timing means switch, and connections including the same, said connections including the control means switch in inoperative position, and the timing means, said timing means being adapted to close said scavenging switch after the timing means has started, and to maintain it closed for a predetermined time after the second timing means switch has opened, until the timing means returns to its starting condition.
